UNITED STATES PATENT OFFICE.

DORSEY F. ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

BREECH MECHANISM.

1,310,045.

Specification of Letters Patent.

Patented July 15, 1919.

Application filed March 15, 1916. Serial No. 84,348.

To all whom it may concern:

Be it known that I, DORSEY F. ASBURY, a citizen of the United States, residing at Washington, District of Columbia, have invented certain new and useful Improvements in Breech Mechanisms; and I do hereby declare the following to be a full, clear, and exact description of the invention, such as will enable others skilled in the art to 10 which it appertains to make and use the same.

My invention relates to breech mechanisms.

The objects of my invention are to move 15 the plug longitudinally far enough to get the gas check out of its seat so that a substantially cylindrical seat may be employed, the slight slope of the seat being used for entering clearance; to rotate the plug while 20 it is moved longitudinally in order to translate its longitudinal movement to rotary movement and vice versa; to provide cam devices between the plug and carrier to move the plug longitudinally and to rotate same 25 during its longitudinal movement; to provide cam devices between the plug and carrier to rotate the plug and move same longitudinally during its rotary movement; to provide cam devices between the plug and 30 carrier for translating the longitudinal movement of the plug to rotary movement and vice versa; to use the energy stored in the plug during carrier movement toward the breech to move the plug longitudinally 35 while the carrier is at rest against the gun and to translate said energy during said longitudinal movement to plug rotating energy; to translate the energy in the plug due to rotary movement to energy to move 40 the plug longitudinally and to use the translated energy to help move the breech mechanism from the gun breech; to translate the energy stored in the plug during carrier movements to plug rotating energy while 45 the carrier is at rest; to provide a cam device including a roller on the plug and a cam on the carrier for translating the longitudinal movement to rotary movement and

vice versa; to have the cam on the carrier bear against the gun during the action of 50 the cam device; to provide a structure whereby the reaction of the cam device between the plug and carrier tends to hold the carrier against the gun during the action of the cam device; to provide means 55 for rotating the plug and cam devices between the plug and carrier for moving the plug longitudinally while it is rotated by said means; to provide a reverse cam device between the plug and gun to prevent the 60 plug and carrier from moving away from the gun while the cam device between the plug and carrier is coacting; to extend the cam device between the plug and carrier so it will coact during the total rotary movement 65 of the plug; to hold the plug against rotary movements while the carrier is away from the gun, by the cam device between the plug and carrier; to hold the plug from longitudinal movement with respect to the 70 carrier while the carrier is away from the gun; and to provide energy translating cam devices between the plug and carrier so that any adjustment at the hinge will not affect the adjustment of the cam device. 75

In the drawings chosen to illustrate my invention, the scope whereof is pointed out in the claims—

Figure 1 is a rear elevation of a gun embodying my invention, the breech mechanism being shown locked; 80

Fig. 2, a horizontal section through a portion of the breech, the plug being unlocked and withdrawn.

Fig. 3, a section on the line 3—3 of Fig. 2. 85
Referring to the drawings A is the gun, B the breech plug and C the swinging carrier which latter embodies a spindle C'. The plug B is mounted on the spindle C' for both rotatable and longitudinal movements. 90 Slidable in the bore of the spindle C' is the stem 10 of a mushroom 11 and confined between the plug B and mushroom 11 is a gas check 12 of the De Bange type. Forward sliding movement of the mushroom 11 and 95 stem 10 relative to the plug is limited by

means of a mushroom stem nut 13 which is adapted to engage a cup 14 acting against compression rods 15 which latter in turn act against the plug B all as is fully described in 5 my U. S. Patent Number 1,186,266, granted June 6, 1916. The plug B is adapted to be rotated by means of a crank shaft 16 operatively connected to a crosshead 17 slidably mounted in the plug and rotated through the medium 10 of a handle 18 all as fully described in U. S. Letters Patent 1,020,849 granted to George L. Smith and myself March 19, 1912. It will however be observed that I can employ any suitable means for rotating the plug.

15 In order to employ a gas check and gas check seat with very little taper in breech mechanisms of the general type disclosed provision must be made for moving the plug longitudinally while the pad is in the seat. 20 To this end I provide on the free end of the carrier C an extension 19 so shaped as to produce an outer cam surface 20 and an inner cam surface 21 corresponding in shape to the outer cam face. The extension 19 also 25 embodies a reverse cam surface 22 for a purpose that will presently appear. The plug B is provided at its rear end with a radial passage 23 in which is detachably secured by a screw 24 a journal pin 25. Mounted on the 30 inner end of the pin 25 for coöperation with the cam surface 21 is a roller 26 while another roller 27 is mounted on the outer end of said pin for coöperation with the cam surface 20. Also mounted on the pin 25 outwardly of the roller 27 is another roller 28 adapted to coact with a reverse cam 29 mounted on the gun A. Pivotaly mounted on the outer end of the extension 19 is a 35 spring latch 30 which, when the carrier is 40 away from the gun, is normally held in engagement with the roller 28 to prevent the plug moving longitudinally. This latch 30 is provided with a tail 31 which engages the gun during final closing movement of the 45 carrier and rocks the latch so that when the carrier is closed the latch is held out of engagement with the roller 28 and also out of the path of travel of said roller. It will also be observed that when the plug 3 is unlocked 50 and in its rearmost position the surface 22 coacting with the roller 27 serves as a lock to secure the plug against locking rotation until the plug moves forward longitudinally.

Assuming that the breech mechanism is 55 being closed and that the parts have reached the position shown in Fig. 2 it will be apparent that as the carrier C has reached the limit of its closing movement the energy stored in the plug B will move the latter 60 longitudinally and operate the cam devices on the plug and carrier to translate such energy to plug rotation energy and thereby effect locking of the plug. In opening the breech of the gun it will be apparent that

during unlocking rotation of the plug effected by the crank shaft 16 the cam devices on the plug and carrier will coact to move said plug longitudinally to the rear and at the limit of this longitudinal movement the plug abuts the carrier and initiates opening 70 movement thereof. I construct portions of the cam surfaces 20 and 21 with a variable lead which portions coact with the rollers 26 and 27 respectively while the plug threads are disengaged from the screw box threads so 75 that at such times the plug B, in opening and closing the breech mechanism, will be rotated and moved longitudinally in varying ratio. In other words in closing the breech and when the plug threads are disengaged 80 from the screw box threads the longitudinal movement of the plug decreases as the rotation increases, while in opening the breech the rotation of the plug decreases while the longitudinal movement increases. 85

When the breech is opened and closed rapidly the forward resultant of the reactionary force of the cam devices on the plug and carrier during their coaction tends to hold the carrier to the gun. In the event the 90 breech is opened and closed very slowly, in which instances very little inertia is present in the plug, the engagement of the roller 28 with the cam 29 holds the carrier to the gun during the coaction of the cam devices on the 95 plug and carrier.

It will be noted that the roller 26 is always in engagement with the cam surface 21 and thereby serves to hold the carrier to the plug at all times. By removing the pin 25 when 100 the plug B is locked and thereby disengaging the roller 26 it will be apparent that the carrier can be removed bodily from the gun by simply removing the nut 13 from the stem 10 and the hinge pin of the carrier from its 105 bearings.

What is claimed is:—

1. In a breech mechanism, the combination of a carrier, a breech plug mounted on the carrier for both rotatable and longitudinal movements, and means operating between the plug and carrier whereby successive units of either movement of the plug will produce varying amounts of the other movement. 110

2. In a breech mechanism, the combination of a carrier, a breech plug mounted on the carrier for both rotatable and longitudinal movements, and means between the plug and carrier for translating one movement of the plug to the other movement of the plug in a varying ratio with respect to the first movement. 120

3. In a breech mechanism, the combination of a carrier, a breech plug mounted on the carrier for both rotatable and longitudinal movements, and variable lead cam devices between the plug and carrier for trans- 125

lating the energy of one movement of the plug to produce the other movement of the plug.

4. In a breech mechanism, the combination of a carrier, a breech plug mounted on the carrier for both rotatable and longitudinal movements, and means between the plug and carrier for translating the energy of one movement of the plug to produce the other movement of the plug in a varying ratio with respect to the first movement.

5. In a breech mechanism, the combination of a carrier, a breech plug mounted on the carrier for both rotatable and longitudinal movements, and cam devices between the plug and carrier for translating the energy of one movement of the plug to produce the other movement of the plug in a varying ratio with respect to the first movement.

6. In a breech mechanism, the combination of a carrier, a breech plug mounted on the carrier for both rotatable and longitudinal movements, and variable lead cam devices between the plug and carrier for translating the stored energy of one movement of the plug to produce the other movement of the plug.

7. In a breech mechanism, the combination of a carrier, a breech plug mounted on the carrier for both rotatable and longitudinal movements, and means between the plug and carrier for translating the stored energy of one movement of the plug to produce the other movement of the plug in a varying ratio with respect to the first movement.

8. In a breech mechanism, the combination of a movable carrier, a breech plug mounted on the carrier for both rotatable and longitudinal movements, a gas check device, and means operated, after the carrier is closed, by the energy stored in the plug to produce combined rotary and longitudinal movements of the plug in varying ratio.

9. In a breech mechanism, the combination of a movable carrier, a breech plug mounted on the carrier for both rotatable and longitudinal movements, and a variable lead cam device operated, after the carrier is closed, by the energy stored in the plug to impart rotary movement to the plug as it moves forward.

10. In a breech mechanism, the combination of a movable carrier, a breech plug mounted on the carrier for both rotatable and longitudinal movements, and means operated, after the carrier is closed, by the energy stored in the plug to produce combined rotary and longitudinal movements of the plug.

11. In a breech mechanism, the combination of a movable carrier, a rotatable breech plug, and a device for translating the energy stored in the plug during closing of the breech mechanism to plug rotation energy,

said device comprising a roller and a cam 65 one of which is mounted on the plug and the other on the carrier.

12. In a breech mechanism, the combination of a movable carrier, a rotatable breech plug, and coacting cam devices on the plug 70 and carrier for translating the energy stored in the plug during closing of the breech mechanism to plug rotation energy.

13. In a gun breech mechanism, the combination of a movable carrier, a rotatable 75 breech plug, and coacting cam devices on the plug and carrier for translating the energy stored in the plug during closing of the breech mechanism to plug rotation energy, the cam device on the carrier abutting the 80 gun during coaction of the cam devices in both opening and closing the breech mechanism.

14. In a breech mechanism, the combination of a carrier, a breech plug mounted on 85 the carrier for both rotatable and longitudinal movements, and a variable lead cam device between the plug and carrier for translating one movement of the plug to the other movement in a varying ratio with respect to the first movement.

15. In a gun breech mechanism, the combination of a movable carrier, a rotatable breech plug, and coacting cam devices on the plug and carrier, the reaction of the cam devices during rotation of the plug in either 95 direction tending to hold the carrier against the gun.

16. In a breech mechanism, the combination of a movable carrier, a rotatable breech 100 plug, and cam devices on the plug and carrier for translating the energy stored in the plug during closing of the breech mechanism to plug rotation energy, said cam devices coacting during substantially the entire 105 rotary movement of the plug in either direction.

17. In a breech mechanism, the combination of a movable carrier, a rotatable breech plug, and cam devices on the plug and carrier for translating the energy stored in the plug during closing of the breech mechanism to plug rotation energy, said cam devices coacting during the entire rotary movement of the plug in either direction and serving to 115 hold the carrier to the plug when the plug is in locked position.

18. In a breech mechanism, the combination of a movable carrier, a rotatable breech plug, and means automatically operating 120 after the carrier is closed to translate the energy stored in the plug during closing movement of the breech mechanism to plug rotation energy.

19. In a breech mechanism, the combination of a movable carrier, a rotatable breech plug, and cam devices for translating the energy stored in the plug during the closing

movement of the breech mechanism to plug rotation energy, the coaction of said cam devices occurring after the carrier is closed.

20. In a gun breech mechanism, the combination of a movable carrier, a rotatable breech plug, cam devices on the plug and carrier for translating the energy stored in the plug during closing movement of the breech mechanism to plug rotation energy, and a reverse cam device on the gun coacting with the cam device on the plug to hold the carrier against movement away from the gun during coaction of the cam devices on the plug and carrier.

15 21. In a breech mechanism, the combination of a movable carrier, a breech plug mounted on the carrier for rotatable and longitudinal movements, and cam devices on the plug and carrier for translating the energy stored in the plug during closing movement of the breech mechanism to plug rotation energy, said cam devices operating to hold the breech plug against rotary movement while the carrier is away from 25 the gun.

22. In a breech mechanism, the combination of a movable carrier, a breech plug mounted on the carrier for both rotatable and longitudinal movements, cam devices 30 on the plug and carrier to rotate the plug and move same longitudinally, and means independent of the cam devices for rotating the plug, said means being locked inoperative by the cam devices while the plug is in 35 its rearmost position on the carrier.

23. In a breech mechanism, the combination of a movable carrier, a breech plug mounted on the carrier for both rotatable and longitudinal movements, cam devices 40 on the plug and carrier to rotate the plug and move same longitudinally, and means independent of the cam devices for rotating the plug, said means being locked inoperative by the cam devices while the plug 45 is in its rearmost position on the carrier and unlocked by forward longitudinal movement of the plug relative to the carrier.

24. In a breech mechanism, the combination of a movable carrier, a rotatable and 50 longitudinally movable breech plug, and cam devices for translating the energy of the plug during unlocking rotation to rearward longitudinal movement to move the breech mechanism to open position, the co- 55 action of the cam devices occurring before the opening movement of the carrier is produced by the plug.

25. In a breech mechanism, the combination of a movable carrier, a breech plug 60 mounted on the carrier for both rotary and longitudinal movements, and variable lead cam devices operating after the carrier is stopped to translate the energy stored in the plug during carrier movements toward the

breech to energy to rotate the plug in the 65 locking direction.

26. In a breech mechanism, the combination of a movable carrier, a breech plug mounted on the carrier for both rotary and longitudinal movements, and variable lead 70 cam devices operating before the carrier begins its opening movement to translate the rotary momentum of the plug produced by unlocking rotation to move the plug rearwardly.

75 27. In a breech mechanism, the combination of a movable carrier, a rotatable breech plug, cam devices for translating the energy stored in the plug during closing of the breech mechanism to plug rotation energy, 80 and a latch normally locking said cam devices inactive and releasable by engagement with the gun as the carrier completes its closing movement.

85 28. In a breech mechanism, the combination of a movable carrier, a rotatable breech plug, coacting cam devices on the plug and carrier for translating the energy stored in the plug during closing of the breech mechanism to plug rotation energy, and a latch on the carrier normally engaging the cam device on the plug to hold same against movement relatively to the cam device on the carrier, said latch being moved to released position by engagement with the gun 95 as the carrier completes its closing movement.

99 29. In a gun breech mechanism, the combination of a movable carrier, a rotatable and longitudinally movable breech plug, co- 100 acting cam devices on the plug and carrier to rotate the plug and move same longitudinally, and a cam device on the plug and gun operating to hold the carrier against movement away from the gun during longitudinal 105 movement of the plug.

30. In a breech mechanism, the combination of a movable carrier, a breech plug mounted on the carrier for both rotary and longitudinal movements, and variable lead 110 cam devices operating before the carrier begins its opening movement to translate the energy of the plug due to unlocking rotation to energy to move the breech mechanism in an opening direction.

115 31. In a breech mechanism, the combination of a carrier, a breech plug mounted on the carrier for both rotatable and longitudinal movements and having a non-threaded connection with the carrier, and means whereby either movement of the plug will produce the other movement.

120 32. In a breech mechanism, the combination of a carrier, a breech plug mounted on the carrier for both rotatable and longitudinal movements and having a non-threaded connection with the carrier, and means between the plug and carrier for translating 125

one movement of the plug to the other movement.

33. In a breech mechanism, the combination of a carrier, a breech plug mounted on the carrier for both rotatable and longitudinal movements and having a non-threaded connection with the carrier, and cam devices between the plug and carrier for trans-

lating the energy of one movement of the plug to produce the other movement.

In testimony whereof I affix my signature, in the presence of two subscribing witnesses.
